UNITED STATES PATENT OFFICE.

WILLIAM SHEAHAN, OF OCEAN FALLS, BRITISH COLUMBIA, CANADA; LAMAR TOOZE, ADMINISTRATOR OF SAID WILLIAM SHEAHAN, DECEASED, ASSIGNOR TO JOSEPH W. SHEAHAN, OF LOS ANGELES, CALIFORNIA; MARIE B. TOOZE, OF EUGENE, OREGON; EDWARD K. SHEAHAN, OF LOS ANGELES, CALIFORNIA; AND LOUISE M. SHEAHAN, OF EUGENE, OREGON.

DEVICE FOR REELING PAPER AFTER BEING CALENDERED.

Application filed June 14, 1923. Serial No. 568,219.

To all whom it may concern:

Be it known that I, WILLIAM SHEAHAN, a citizen of the United States, and a resident of the city of Ocean Falls, Province of British Columbia, Dominion of Canada, have invented a new and useful Improvement in Devices for Reeling Paper After Being Calendered, of which the following is a specification.

10 One of the main objects of my invention is to provide a simple and efficient mechanism for reeling the paper after being calendered in a paper making machine.

A further object is to provide a reel for paper making machines which is driven by frictional contact with one of the calender rolls, and is removably mounted and horizontally slidable on its supporting frame, so that it can be slid out of contact from 15 the calender roll, and at the same time rotated at a predetermined rate of speed, and thus providing for the placing of another reel in front of the wound reel and in operative contact with the calender roll.

20 25 A further object is to provide a mechanism whereby paper from a paper making machine is removed from the calender rolls onto the winder roll and as the winder bar increases in diameter due to accumulation of 30 paper, an unfilled roll being smaller in diameter can be placed under the moving paper and allow the paper to be wound on this new roll in a minimum amount of time.

35 40 A further object is to provide the combination of a driving roll, a winder roll for winding an endless sheet of material led from the driving roll, said winder roll being removably mounted and horizontally slidable so as to be placed in frictional contact with or spaced from the driving roll, releasable means for holding the winder roll in its frictional contact but adapted to yield relatively to the amount of material wound on the winder roll whereby when 45 50 the winding of the winder roll is completed the same can be moved from against the driving roll and allow an unfilled roll to be introduced between the first mentioned winder roll and the driving roll, also means provided for continuing the rate of revolution imparted to the winder roll by the driving roll at the instant the former is

removed from the latter to permit said introduction of another winder roll.

The above features and others are illustrated in the accompanying drawings, in which:

Fig. 1 is a side elevation of the mechanism with parts broken away;

Fig. 2 is a plan view of the winder bar mechanism;

Fig. 3 is an end elevation of this mechanism shown in conjunction with the lower calender roll of a paper making machine;

Fig. 4 is a fragmentary sectional view taken on the line 4-4 of Fig. 3;

Fig. 5 is a fragmentary sectional view taken on the line 5-5 of Fig. 3;

Fig. 6 is a fragmentary sectional view taken on the line 6-6 of Fig. 3;

Fig. 7 is a fragmentary section taken on the line 7-7 of Fig. 3;

Fig. 8 is a partial end elevation taken on the line 8-8 of Fig. 2;

Fig. 9 is a fragmentary end elevation taken on the line 9-9 of Fig. 2;

Fig. 10 is a perspective view of a detail of construction;

Figs. 11, 12 and 13 are perspective views showing the lateral frames which support the mechanism;

Figs. 14, 15, 16, 17, 18, 19 and 20 are views showing details of construction.

The winding mechanism is symmetrical on both sides except that the left hand side is the reverse of the right hand side and it is therefore to be understood that any parts shown on one side have a corresponding part on the opposite. The mechanism on one side only will therefore be described and the parts on the opposite side will be similar except that they are the opposite hand.

The mechanism is mounted on base *a*. 95 Frames *b*, *c* and *d* are mounted on base *a*. The drive shaft *e* is journaled in the base *a* and a sprocket is mounted thereon. Stub shafts *g* are journaled in the upper parts of the frames *b*, *c* and *d*. They are mounted in adjustable bearings *h* so as to take up any slack in the chains. These bearings are adjusted by screws *i*. Sprockets *j* are mounted on the stub shafts *g* and are positioned in vertical alinement with the sprock-

ets *f*. The drive chain *k* is mounted over these sprockets. Sprockets *l* are also rigidly mounted on the shafts *g* between the frames *b* and *c*. Another stub shaft *m* is passed thru the frames *b*, *c* and *d* and journaled therein. A sprocket *n* positioned between the frames *b* and *c* is mounted freely on the shaft *m* and in line with the sprocket *l*. A chain *o* is mounted over the sprockets *n* and *l* and between the frames *b* and *c*. Another sprocket *p* is mounted freely on the shaft *m* between the frames *c* and *d*. Another stub shaft *q* is mounted in the slidable bearing boxes *r* which slide in the frames *c* and *d*. The sprocket *q'* is rigidly mounted to the shaft *q*. These bearing boxes are made of side pieces *r'* and separate end pieces *r²* and *r³*. A screw *s* is fixed to the end pieces *r²* and *r³* and is mounted in the frame *d*. The brake shaft *t* is mounted thru the bases *a* and has sprockets *u* fixed thereon. A chain *v* is mounted about the sprockets *p*, *q'* and *u*. The brake shaft *t* is supported in the middle by a bearing *w*. A pulley *x* is fixed to the brake shaft and an adjustable friction band *y* is placed around it. Friction blocks *z* are fastened to the band at *y* and provides a friction surface on the face of the pulley. A lug *2* is fastened to the band *y* and the rod *3* is attached to this lug. A compression spring *4* mounted in the container *5* exerts a tension in the rod *3*. As the lug is brought around in a counter-clock wise direction the spring *4* is compressed because the block *6* holds it on one end and the container *5* holds on the bottom and on the other end. The shaft *q* is rotated by the ratchet lever *7*. Manual pressure on the ratchet lever *7* causes the shaft *q* to be partly rotated thereby turning the sprocket *q'* which in turn gives movement to the chain *v* and thereby rotates the brake shaft *t* thru the sprocket *u*. Because the brake band pulley *x* is keyed to the shaft *d* and the adjustable friction band *y* is mounted to this pulley any rotation in the brake shaft results in compression being given to the spring *4* and when the proper amount of pressure is brought against the spring *4* the bolts *8* are placed thru the chain *v* so as to maintain the tension in this chain. This bolt *8* is mounted on the frame *c* and slips thru a hole *9*. It is operated by the link mechanism *10*. The winder bar *11* is mounted on the shaft *12* which is mounted in the slidable boxings *13* which slide in the recesses *14* and *15* in the top of the frames *c* and *d*. A sprocket *16* is rigidly mounted to the shaft *12* and is in vertical alinement with the chain *o* but spaced slightly above it. The fulcrumed rod *17* is adapted to raise the chain *o* so that it will connect with the sprocket *16*. This rod *17* is fulcrumed as at *18* and is operated by the cam *19* which is controlled by the slotted lever *20* and the

pusher rod *21*. A hook *22* is mounted in the slidable boxing *13* and the cable *23* mounted about the sheave *24* provides means for moving the boxing along the recessed portions *14* and *15*. This pulley is mounted in a support *25* which is mounted to the frames *b*, *c* and *d*. An eye-bolt *26* is placed in the top of the slidable bearings *13* and provides a means for moving the winder bar out of position.

The operation is as follows: The winder bar with its bearings is placed in position in the recesses *14* and *15* and is pushed against the calender roll so that it is in frictional contact with it. Manual pressure is then exerted on the ratchet lever *7* and the spring *4* is compressed. The pin *8* is then dropped in place in the links of the chain *v* and the compression force which is set up in the spring *4* results in a tension being placed in the chain *v*, and thus the winder bar *11* is held tightly against the calender roll. The winder bar is thus caused to rotate merely by the frictional contact against the calender roll. As the winder bar rotates winding up the paper it is forced away from the calender roll by the paper causing the roll to grow larger in diameter. This sliding away from the calender roll is resisted by the action of the compression in the spring *x* and further compression takes place until the slipping occurs between the friction blocks and the pulley. This action keeps the winder bar in constant pressure against the calender roll. When the winder bar has wound up the required amount of paper it must be moved away from the calender roll so that a new winder roll can be inserted. The pusher rod can then be pushed in which throws the cam element up and forces the chain *o* upward and in connection with the sprocket *16*. Thus the winder roll can be rotated by this drive chain *o*. The bolt *8* can then be removed from between the links of the chain *v* and the winder bar can be removed from frictional contact with the calender roll. The cable *23* is connected with any suitable mechanism which can move this roll backward. A new winder bar can then be placed adjacent the calender roll and the paper broken and placed on the new roll and the old one can then be taken away.

I claim:

1. In devices of the character described the combination with a driving roll, a winder roll for winding an endless sheet of material led from the driven roll, said winder roll being removably mounted, and horizontally slidable, for placing the winder roll in frictional contact with, or spacing it from, the driving roll, whereby when the winding of the winder roll is completed the same may be moved from the driving roll and other journal boxes carrying another

winder roll introduced between the first mentioned winder roll and the driven roll, and means for continuing the rate of revolution imparted to the winder roll by the 5 driven roll at the instant the former is moved from the latter to permit said introduction of another winder roll.

2. In devices of the character described the combination with a driving roll, journal 10 boxes, a winder roll carried thereby for winding an endless sheet of material led from the driven roll, horizontal ways on which the journal boxes are removably mounted, and also slidably thereon for placing the winder roll in frictional contact 15 with, or spacing it from, the driving roll, whereby when the winding of the winder roll is completed the same may be moved from the driving roll and other journal 20 boxes carrying another winder roll introduced between the first mentioned winder roll and the driven roll, and means for continuing the rate of revolution imparted to the winder roll by the driven roll at the 25 instant the former is moved from the latter to permit said introduction of another winder roll.

3. In devices of the character described the combination with a driving roll, journal 30 boxes, a winder roll carried thereby for winding an endless sheet of material led from the driven roll, horizontal ways on which the journal boxes are removably mounted and also slidably thereon for placing the winder roll in frictional contact 35 with, or spacing it from, the driving roll, releasable means for holding the winder roll in its said frictional contact, but adapted to yield relatively to the amount of material 40 wound on the winder roll, whereby when the winding of the winder roll is completed the same may be moved from the driving roll and other journal boxes carrying another winder roll introduced between the 45 first mentioned winder roll and the driven roll, and means for continuing the rate of revolution imparted to the winder roll by the driven roll at the instant the former is moved from the latter to permit said introduction of another winder roll.

4. A device of the character described comprising, a frame, journal boxes removably mounted on the frame, and horizontally slidably thereon, means for moving 55 the journal boxes towards one end of the frame, releasable means yieldingly resisting the movement of the journal boxes in the opposite direction, and means, normally inactive, operable to revolve the shaft journaled in said journal boxes at a fixed rate.

5. A device of the character described comprising, a frame, journal boxes removably mounted on the frame, and horizontally slidably thereon, a winder roll journaled in said journal boxes, means for mov- 65

ing the journal boxes towards one end of the frame, releasable means yieldingly resisting the movement of the journal boxes in the opposite direction, a sprocket on one end of the winder roll, a driven sprocket 70 chain, carried by said frame, normally out of contact with said sprocket, and means for placing said sprocket chain into engagement with said sprocket so as to drive the same. 75

6. A device of the character described comprising, a frame, journal boxes removably mounted on the frame, and horizontally slidably thereon, means for moving the journal boxes towards one end of the 80 frame, releasable means yieldingly resisting the movement of the journal boxes in the opposite direction, means for moving the journal boxes towards the opposite end of the frame, and means, normally inactive, 85 operable to revolve the shaft journaled in said journal boxes at a fixed rate.

7. In a winder roll mechanism the combination of, a frame having two sides spaced apart, a journal box removably mounted on 90 each frame side and horizontally slidably thereon, means carried by each frame side for moving the journal boxes in one direction, such means comprising sprockets and a chain running thereon, means for manually revolving one of the sprockets, an articulated arm on each journal box and a pin carried by such arm for inserting in the adjacent sprocket chain so as to operatively connect the journal box thereto. 95

8. In a winder roll mechanism the combination of, a frame having two sides spaced apart, a journal box removably mounted on each frame side and horizontally slidably thereon, a winder roll journaled in said 100 journal boxes, sprockets provided at the ends of the winder roll, means carried by each frame side for moving the journal boxes in one direction, said means being operatively connected to operate in unison, 110 and means, normally inactive, operable to revolve the winder roll at a fixed rate.

9. In a winder roll mechanism the combination of, a frame having two sides spaced apart, a journal box removably mounted on 115 each frame side and horizontally slidably thereon, a winder roll journaled in said journal boxes, sprockets provided at the ends of the winder roll, means carried by each frame side for moving the journal 120 boxes in one direction, said means being operatively connected to operate in unison, and a driven sprocket chain and means for causing the same to engage with the sprockets of said winder roll so as to drive the 125 same.

10. In a winder roll mechanism the combination of, a frame having two sides spaced apart, a journal box removably mounted on each frame side and horizontally slidably 130

- thereon, a winder roll journaled in said journal boxes, sprockets provided at the ends of the winder roll, means carried by each frame side for moving the journal boxes in one direction, such means comprising sprockets and a chain running thereon, means for manually revolving one of the sprockets, means for connecting the journal boxes to the sprocket chains, spring controlled means yieldingly resisting the reverse movement of said sprocket chains, a driven sprocket chain and means for causing the same to engage with the sprockets of said winder roll so as to drive the same.
- 5 10 15 20 25
11. In a winder roll mechanism the combination of, a frame having two sides spaced apart, a journal box removably mounted on each frame side and horizontally slidable thereon, a winder roll journaled in said journal boxes, sprockets provided at the ends of the winder roll, means carried by each frame side for moving the journal boxes in one direction, such means comprising sprockets and a chain running thereon, one of the sprockets of each frame side being mounted on a common shaft extending thru both frame sides, means for manually revolving one of the sprockets, means for connecting the journal boxes to the sprocket chains, a rigid pulley on said common shaft, 30 a band adapted for clamping on such pulley, said band being connected to restraining means, a driven sprocket chain and means for causing the same to engage with the sprockets of said winder roll so as to 35 drive the same.
12. In a winder roll mechanism, a frame comprising two spaced sides, each comprising a base and an upper part mounted thereon, the upper part comprising parallel 40 frame members arranged side by side, spaced apart, a journal box removably mounted on each frame side and slidably thereon, means for moving the journal boxes towards one end of the frame, means, normally inactive, operable to revolve the device journaled in said journal boxes at a fixed rate, the means for effecting the movement of the journal boxes, and the revolution of the device journaled therein being 45 in part located in the spaces between the frame members of the upper part of the frame sides.

WILLIAM SHEAHAN.
